ATTORNEY

UNITED STATES PATENT OFFICE.

WILSON C. BERGER, OF CANTON, OHIO.

EAVES-TROUGH HANGER.

SPECIFICATION forming part of Letters Patent No. 350,909, dated October 19, 1886.

Application filed March 24, 1886. Serial No. 196,325. (No model.)

To all whom it may concern:

Be it known that I, WILSON C. BERGER, a citizen of the United States, residing at Canton, in the county of Stark and State of Ohio, have invented certain new and useful Improvements in Eaves-Trough Hangers; and I do hereby declare that the following is a full, clear, and exact description of the same, reference being had to the annexed drawings, making a part of this specification, and to the letters and figures of reference marked thereon, in which—

Figure 1 is a perspective view showing hanger attached to an eaves-trough. Fig. 2 is a transverse section of an eaves-trough, showing hanger attached thereto. Fig. 3 is a transverse section of hanger through line 4 4, Fig. 2. Fig. 4 is a transverse section through line y y, Fig. 2.

20 The present invention has relation to eaves-trough hangers; and its nature consists in the different parts and combination of parts, hereinafter described, and particularly pointed out in the claims.

25 Similar letters of reference indicate corresponding parts in all the figures of the drawings.

In the accompanying drawings, A represents the eaves-trough, which may be constructed in the ordinary manner, and to the trough A is attached the hanger B, substantially as shown in the drawings. The hanger B is formed of sheet metal, and for the purpose of strengthening the hanger the bent or beveled portions a are formed substantially as shown.

30 For the purpose of strengthening the grasp b, which embraces the bead of the trough, the ribs c c are formed, which may be substan-

tially as shown. These ribs c c may be formed 40 by means of a suitable die.

The end of the hanger B, which is attached to the raw edge of the trough A, is provided with the hook or grasp d, which embraces the lip d', as shown in Figs. 1 and 2. The lip d' 45 is formed by bending a portion of the trough A outwardly. It will be understood that one of the lips d' is formed at each place where a hanger is to be located.

In use the grasp b is properly adjusted on 50 the bead of the trough A, when the hook or grasp d is adjusted as shown in Figs. 1 and 2.

It will be seen that by my peculiar arrangement I am enabled to form an eaves-trough hanger of a single piece of metal. It will be 55 seen that the lip d' is bent outwardly and downwardly.

Having now fully described my invention, what I claim as new, and desire to secure by Letters Patent, is—

1. The hanger B, formed of a single piece of sheet metal, having the grasp b, the bent or beveled portions a, and the hook or grasp d, for receiving the outwardly-formed lip d', substantially as and for the purpose specified. 60

2. The hanger B, formed of a single piece of sheet metal, having the grasp b, provided with the ribs c c, the bent or beveled portion a, and the hook or grasp d, for receiving the outwardly-formed lip d', substantially as and 65 for the purpose specified.

In testimony that I claim the above I have hereunto subscribed my name in the presence of two witnesses.

WILSON C. BERGER.
